REMOVAL OF METAL CONTAMINANTS FROM HIGH BOILING OILS

Raymond L. Heinrich, Baytown, Tex., assignor, by mesne assignments, to Esso Research and Engineering Company, Elizabeth, N.J., a corporation of Delaware

Application December 27, 1955, Serial No. 555,628

11 Claims. (Cl. 208—253)

The present invention is directed to a method for removal of organic contaminants from high boiling oils containing same. More specifically, the invention is concerned with removal of metal contaminants and compounds which form stack solids and the like from high boiling residual oils and asphalts. In its more specific aspects, the invention is concerned with recovery from residual petroleum fractions of valuable oils and products which are substantially free of compounds forming stack solids and other contaminants.

The present invention may be briefly described as a method for removing deleterious organic compounds, such as metal contaminants and compounds, which form stack solids on burning the oils, from petroleum fractions the major portion of which boils above about 900° F. containing the metal contaminants and the stack solid-forming compounds. In the present invention the petroleum fractions, as have been described before, are contacted at a temperature in the range from about 750° to about 825° F. with a sulfur-insensitive hydrogenation catalyst in the presence of hydrogen and at a sufficient pressure and space velocity to form coky particles separable from the contacted fraction and containing said metal contaminants and stack solid-forming compounds. The contacted fraction is removed from contact with the catalyst and the coky particles are then separated from the contacted fraction to allow recovery of the contacted fraction to obtain a fraction containing a substantially reduced amount of the metal contaminants and the stack solid-forming compounds.

The temperatures at which the present invention may be conducted suitably range from about 750° to about 825° F. with a preferred temperature range from about 775° to about 825° F. It is preferred to operate with a temperature gradient in the range from 775° to 825° F.

The reaction involved in the present invention is an exothermic reaction wherein the outlet temperature of the reaction zone is preferably about 50° F. greater than that of the inlet to the reaction zone. A temperature gradient in the reaction zone where the temperature increases by about 50° F. is particularly beneficial.

It is quite desirable and necessary to operate within the temperature range given. Otherwise, below about 750° F. there is loss of conversion and the deleterious compounds are not formed into a readily separable condition. Above about 825° F. coking and fouling of the catalyst bed occurs which may make the process completely inoperable.

In practicing the present invention, it has been found that, with domestic feed stocks of the type mentioned before, such as those originating in Continental United States, such as those from heavy Texas crude petroleum contaminated with metals and containing components boiling below 900° F., a temperature range from about 750° to about 800° F. may be employed and preferably a temperature gradient within that range. However, a temperature gradient in the range from 750° to 800° F. does not always give the best results and it is preferred

that a temperature in the range from 775° to 825° be employed for domestic petroleum fractions treated in the practice of the present invention. Where heavy petroleum fractions, such as those originating in Venezuela boiling above about 900° F., are employed, a preferred temperature range is from 775° to 825° F. and a temperature gradient within that range.

Pressures employed in the practice of the present invention may range from about 400 to 3000 pounds per square inch gauge with a preferred range from 800 to 2000 pounds per square inch gauge. Quite satisfactory results are obtained in the range from about 800 to about 1600 pounds per square inch gauge.

The petroleum fraction contacts the catalyst at a space velocity in the range from about 0.25 to about 5 volumes of petroleum fraction per volume of catalyst per hour with a preferred space velocity in the range from about 0.5 to about 2 volumes of petroleum fraction per volume of catalyst per hour.

The feed stocks employed in the practice of the present invention are suitably petroleum fractions which are contaminated with metals, such as nickel, vanadium, iron which may comprise porphyrins and difficultly soluble carbonaceous material. These contaminated materials are usually the fractions boiling above about 900° F. and may include gas oils, reduced crudes, vacuum flashed crude petroleum residua, extract and raffinate fractions from solvent extraction, fractions of heavy crude petroleum, fractions obtained by deasphalting crude petroleum fractions and heavy crude petroleum obtained by other separatory processes; also, asphalt from Hawkins crude, such as found in Texas, crude petroleum residua from Venezuelan crude, such as Bachaquero, and other fractions which contain metal contaminants and/or compounds which tend to form stack solids on combustion of fuel oil.

Other heavy fractions may be employed in the practice of the present invention. For example, asphaltic fractions such as those obtained from Texas crude petroleums may be used. Suitably, the feed stock may contain some lighter fractions but usually will consist essentially of the heavier fractions of which about 50% to 100% by volume boil above about 900° F. For example, a suitable feed stock for the present invention is a mixture of West Texas and Coastal crude asphalts having following composition:

Table I

	Vol. percent
50 IBP—430° F. -----	11.8
430—650° F. -----	6.3
650—950° F. -----	5.9
950—1015° F. -----	5.8
1015° F. + -----	70.2
	100.0

It will be noted that this feed mixture contained 76% by volume of fractions boiling about 950° F. Thus, it is contemplated that the major portion of the feed will boil above about 900° F.

The catalyst employed in the present invention is suitably a sulfur-resistant or insensitive hydrogenation catalyst and may be a supported sulfur-resistant or insensitive hydrogenation catalyst. As examples of the supported type catalyst may be mentioned cobalt or nickel molybdate, molybdenum oxide, molybdenum sulfide, cobalt or nickel vanadate, vanadium sulfide, cobalt nickel, or tungsten sulfides or mixtures thereof, and the like, suitably supported on supports, such as alumina, magnesia, carbon, zirconia, diatomaceous earth, and the like. The catalytic material suitable for support on the catalyst is in an

amount in the range from about 2% to about 25% by weight of the catalyst. The non-supported sulfur resistant hydrogenation catalyst may suitably include cobalt sulfide, nickel sulfide, tungsten sulfide, molybdenum sulfide or mixtures thereof.

The practice of the present invention involves the employment of hydrogen. A hydrogen-containing gas or a pure hydrogen may be employed. The amount of hydrogen used may suitably range from about 1500 to 6000 standard cubic feet per barrel of feed at 60° F. with a preferred amount of the hydrogen being in the range from 2000 to 4000 standard cubic feet per barrel of feed at 60° F.

The present invention will be further illustrated by reference to the drawing in which the single figure is a flow diagram of a preferred mode.

Referring now to the drawing, numeral 11 designates a charge line by way of which a feed stock of the nature described supra is introduced into the system from a source, not shown. The pump 12 in line 11 pumps the feed stock into a furnace or heater 13 provided with a heating coil 14. Prior to introduction into coil 14, the feed stock has hydrogen admixed therewith introduced thereto by line 15. The mixture of hydrogen and feed stock is heated in heater 13 to a temperature in the range indicated with heat being supplied to the heater 13 by means of gas burners or other heating means 16.

The heated mixture of hydrogen and feed stock is withdrawn from coil 14 by line 17 and is introduced thereby into a reaction zone indicated by the numeral 18 which contains a bed of catalyst 19, such as a cobalt molybdate catalyst supported on alumina. After contact with the catalyst for the specified time, the contacted petroleum fraction discharges from reaction zone 18 by line 20, passes through a heat exchanger or other temperature adjusting means, such as 21, and then is introduced thereby into a separator 22. In separator 22 fixed gases are separated from the liquid material and the fixed gases are withdrawn by line 23 and preferably are recycled by line 15 to line 11. A portion of the fixed gases may be discharged by line 23 by opening valve 24. If desired, make-up hydrogen may be introduced into line 15 by way of line 25 controlled by valve 26.

A particular feature of the present invention is that the specified conditions result in the metal contaminants present in the feed and other deleterious bodies being formed into what is termed "microcoke." This microcoke is readily separable from the contacted fraction but does not, to a large extent, foul the catalyst bed 19. In other words, the microcoke remains suspended in the fraction as it passes through the reaction zone 18 and the separator 22 until a sufficient residence time is provided for gravity settling or a separation treatment is practiced. This microcoke may have particle diameters in the range from about 0.1 to about 1000 microns, preferably 2 to 20 microns. Analysis of the coke showed particle diameters of 5 to 10 microns.

Therefore, in accordance with the present invention, the liquid fraction from separator 22 is discharged therefrom by line 27 into a separation zone indicated generally by the numeral 28. The separation zone may suitably comprise a tank, a precoat filter operated at a high temperature, a centrifuge or a centrifuge-filter or any other separating procedures for separating the microcoke from the contacted fraction. For purposes of illustration only and not by way of limitation, separator 28 may be considered to be a centrifuge operated at a sufficient speed to separate substantially all the microcoke from the contacted fraction. The separator 28 may operate at a temperature in the range from 60 to 600° F., preferably at a temperature in the range from 150° F. to 400° F. Microcoke is withdrawn from separator 28 by line 29 while the liquid contacted fraction is discharged by line 30 into a fractionator zone indicated generally by numeral 31 which may be a single fractional distillation tower

or which may be a plurality of fractional distillation towers, each equipped with suitable internal baffling equipment, such as bell cap trays and the like, wherein intimate contact between liquid and vapor is obtained. Also, 5 fractional distillation zone 31 is understood to include suitable means for inducing reflux and means for cooling and/or condensing the overhead fractions and other fractions separated therefrom.

Temperature and pressure conditions in zone 31 may 10 suitably be adjusted by heating means generally indicated by steam coil 34 to obtain an overhead fraction by way of line 35 which may suitably be a gasoline fraction boiling in the range from 100 to 350° F. and intermediate higher boiling fractions which may be withdrawn by side streams or lines 36, 37 and 38. A fuel oil fraction may 15 be discharged from distillation zone 31 by line 39 controlled by valve 40 for use in industrial and domestic fuels as may be desired. It may be desirable under some conditions, however, to recycle the fraction withdrawn 20 by line 39 to line 11 by way of branch line 41 containing a control valve 42 and pump 43.

The fractions withdrawn by lines 35, 36, 37 and 38 may 25 suitably be used as motor fuels, diesel oils, cracking stocks, and the like. Particularly the heavier fractions will be suitable cracking stocks by virtue of their low contents of metals and by virtue also of their low level of contamination with other deleterious compounds.

It will be seen from the foregoing description taken with the drawings that a new and improved process has 30 been provided by way of which metal contaminants and other deleterious organic compounds, which form stack solids on combustion, are removed from high boiling petroleum fractions. Further, it may be seen that a process has been provided for producing fractions having reduced 35 metal and other contaminant content which are suitable as feed stocks for catalytic cracking operations.

While the present invention has been illustrated with a fixed bed reactor, it is to be clearly understood that the reaction zone 18 may be one of the fluidized powder type wherein the catalyst is suspended in the vaporized 40 feed stock. Also, the catalyst may be suspended in the liquid feed stock under high pressure conditions to form a slurry and treated thereby. Thus, with the fluidized bed or slurry type operation a great advantage may inure to the practice of the present invention in that the microcoke particles are kept in motion and are easily carried out of the reactor in the liquid product.

In order to illustrate the invention further, runs were 45 conducted with an asphalt obtained from Texas crudes which was heated and then contacted with a cobalt molybdate on alumina catalyst at a pressure of about 400 pounds per square inch gauge and under conditions in a reaction zone which encompassed a top temperature of 750° F., a center temperature of 784° F., and a bottom outlet temperature of 801° F. The feed rate of liquid to the reaction zone containing the cobalt molybdate on alumina catalyst was 0.47 v./v./hr. with a hydrogen feed rate of 3280 standard cubic feet per barrel of feed. Under these 50 conditions the metal contaminants in the feed stock were formed and contained in microcoke which visually settled on the bottom of the container into which the product was fed. The total product from this operation had a sulfur content of 1.47 weight percent, a modified naphtha insolubles content of 13.2 weight percent and a gravity of 12.9 API. This may be compared with a feed sulfur 55 of 2.80 weight percent, 12.2 weight percent modified naphtha insolubles, and 6.5° API gravity.

Although the modified naphtha insolubles in the product are substantially the same as that of the feed, the modified naphtha insolubles in the product are separable to a large extent by gravity, filtering or centrifuging, whereas that from the feed is not separable.

Other operations were conducted with the same catalyst under temperature conditions ranging from 750° 70 to 800° F. as compared with temperature conditions from

775° to 825° F. These operations were conducted at 800 pounds per square inch gauge. The results of these runs are presented in the following table which compares conversion conditions of non-microcoking as compared to microcoking:

present invention, operations were conducted at varying pressures on an asphalt from a mixture of West Texas and Coastal crudes (Table I) at temperatures in the range from 750° to 800° F., employing a cobalt molybdate on alumina catalyst as has been described supra. The

Table II

Feed	Asphalt From a Mixture of West Texas ¹ and Coastal Crudes		1,100° F. + Residuum From Bachaquero Crude		
	Conversion Conditions		Feed	Conversion Conditions	
	Non-Micro-coking	Micro-coking		Non-Micro-coking	Micro-coking
Reactor Temperature, ° F.:					
Inlet	750	775		750	775
Outlet	800	825		800	825
Product Yield, Wt. Percent of Total Product:

Sulfur, Wt. Percent	0.48	0.69		1.19	0.83
MNI, Wt. Percent	7.5	7.1		13.1	7.5
Nickel, p.p.m.	33	20	108	72	27
Vanadium, p.p.m.	44	23	15	374	125

MNI is modified naphtha insolubles in the oil.

¹ The composition of this material is given in Table I.

It may be seen from the foregoing Table II that with the asphalt from the West Texas and Coastal crudes the inspections of the total and liquid products showed a substantial improvement for conversion conditions involving microcoking. It will be noted that under the non-microcoking conditions, the modified naphtha insolubles content in the liquid product is substantially the same as that in the total product, while under microcoking conditions the modified naphtha insolubles content in the liquid product is substantially less than that in the total product indicating the separation of the contaminating materials. Comparing the data from the Bachaquero Venezuelan crude under non-microcoking and microcoking conditions, it will be seen that the results are even more striking than for the West Texas and Coastal asphalt. Under non-microcoking conditions the modified naphtha insoluble content was substantially the same whereas under microcoking conditions the modified naphtha insoluble level in the total product was substantially reduced and the modified naphtha insoluble content in the liquid product was even less than that of the total product.

Other inspection characteristics were similarly improved. The lowered nickel and vanadium contents of the liquid products produced under microcoking conditions are especially noteworthy. Nickel and vanadium are considered quite deleterious as contaminants in cracking stocks and in oils such as charged to fluid catalytic cracking operations. The presence of these metal contaminants results in the formation of gaseous and coky products with degradation of the desired products whereas the presence of these materials in fuel oils either for domestic or industrial purposes results in deleterious effects on burners and furnaces.

The data in the several examples are especially noteworthy as to the effect of pressure. It will be seen, considering the first operation at 400 pounds per square inch gauge, that it is possible to operate at a temperature between 750° and 825° F. but at 800 pounds per square inch gauge the preferred temperature range of 775° to 825° F. must be employed. Otherwise, the deleterious contaminants, such as metal and compounds which form stack solids, remain in suspension and solution and are not readily separable either by gravity, filtering or centrifuging from the contacted product.

In order to illustrate the effect of pressure in the

results of these operations are presented in the following table:

Table III

Pressure, p.s.i.g.	Feed	200	300	400	800
Total Liquid Product, Inspections:					
Gravity, °API	6.5	10.0	10.0	12.9	14.5
Sulfur, Wt. Percent	2.80	1.70	1.77	1.47	0.92
MNI, Wt. Percent	12.2	17.4	17.0	13.2	8.9

From these operations it was observed that at 400 pounds per square inch gauge pressure instead of 800 pounds per square inch pressure a significant increase in conversion to distillate was obtained but less desulfurization was obtained than at 800 pounds per square inch gauge pressure. It is particularly significant that at pressures above 400 pounds per square gauge the modified naphtha insolubles content was no greater than that of the feed and microcoking was obtained such that the contaminating particles were easily separable.

At 200 and 300 p.s.i.g. the modified naphtha insolubles content was greatly increased over the feed modified naphtha insolubles content, desulfurization was much less than at 400 or 800 p.s.i.g. and there appeared in the product a finely divided carbonaceous material which partly settled out upon standing. This material was produced in such quantities as to impair operation of the unit through plugging of the catalyst retaining screen and the valves in the product drawoff line. The catalyst displayed a rapid loss in activity during this microcoking at 200 and 300 p.s.i.g. whereas this catalyst deactivation was not detectable in operations at 400 and 800 p.s.i.g. The results indicate that pressures below 400 p.s.i.g. are not practical because of the very frequent air regeneration of the catalyst which would be required. Pressures below 800 p.s.i.g. may be employed if desulfurization and modified naphtha insolubles reduction are not primary considerations, that is if conversion to distillate material is the prime objective.

The modified naphtha insolubles referred to in the specification and in the several examples is a measure of the contaminating particles and may include besides asphaltenes, sulfur, both elemental and combined, metals such as iron, nickel and vanadium present in the feed stock,

The metals may be in the form of organo-metallic compounds. Actually it has been determined that the so-called "microcoke" contains a substantial part of the metals and other contaminating deleterious bodies. The modified naphtha insolubles itself may be described as follows:

(1) 1.0 ± 0.1 gram of the sample to be tested is weighed to the nearest milligram in a clean, dry, tared, 125 ml. glass stoppered Erlenmeyer flask.

(2) Exactly 5 ml. of chemically pure carbon bisulfide is added to the flask. The flask is whirled a number of times to dissolve the sample as completely as possible.

(3) Exactly 100 ml. of 86° naphtha is added to the flask.

86° naphtha is defined as follows: It is cut from a paraffin base crude. It has a gravity in the range from 86° to 88° API. In an Engler distillation, not less than 10% thereof distills over between 95° and 150° F. The aniline point of the naphtha is between 152 and 156 when calculated from the aniline point test on a blend of 35% naphtha and 60% normal heptane.

(4) The stopper is placed in the flask and the latter, with its contents, is shaken vigorously for one minute.

(5) The flask is placed in a water bath such that the water level in the bath is above the liquid level in the flask. The flask remains in the bath for at least two hours at $100^{\circ} \pm 1^{\circ}$ F.

(6) The flask is removed from the water bath and the contents immediately filtered through a tared Gooch crucible. Suction is applied gently at first and is then increased to a pressure of 20 inches of mercury in the filtering flask. Care must be taken to prevent loss of sample during filtration.

(7) The flask and stopper are washed with two 50 ml. portions of 86° naphtha and the washings filtered through the tared crucible.

(8) The crucible, flask and stopper are dried for one hour in an air oven at 221° F., cooled in a desiccator, and weighed to the nearest milligram.

(9) The increase in weight of crucible, flask and stopper represents the total amount insoluble in the naphtha plus CS₂. This is reported as percent of the original sample.

(10) It is preferred to make the test in duplicate, and use the resulting average value, provided the individual results do not differ from the mean by more than 5 percent of the mean. If the individual results do differ by more than 5% of the mean, two additional tests should be made, the least concordant result discarded, and the remaining three averaged.

In order to illustrate the removal of deleterious compounds from feed fractions in accordance with the present invention, microcoke separated by centrifugation from the contacted product was analyzed. In the following table an analysis of a microcoke from an asphalt from West Texas and Coastal crudes is given:

Table IV

Microcoke:

Sulfur, wt. percent	1.56
Modified naphtha insolubles, wt. percent	48.8
Nickel, p.p.m.	170
Vanadium, p.p.m.	160
Iron, p.p.m.	

In another operation microcoke centrifuged from a contacted Bachaquero residuum was analyzed and found to comprise contaminating bodies as indicated in the following table:

Table V

Microcoke:

Sulfur, wt. percent	1.76
Modified naphtha insolubles, wt. percent	44.9
Nickel, p.p.m.	228
Vanadium, p.p.m.	953
Iron, p.p.m.	

From these results it may be seen that the microcoke contains substantial amounts of sulfur, modified naphtha insolubles, nickel, and vanadium and in the case of microcoke from the Bachaquero residuum a substantial amount of iron.

From the foregoing examples and description taken with the drawings, it may be seen that a new and improved process has been devised for treating heavy petroleum fractions or crudes which make the products therefrom quite useful as catalytic cracking stocks and as fuel oils, either for industrial or domestic consumption. The invention is conducted with conventional equipment, does not require major capital investment, and is economical to operate. Therefore, the present invention is of considerable utility and advantage.

The nature and objects of the present invention having been completely described and illustrated, what I wish to claim as new and useful and to secure by Letters Patent is:

1. A method for removing metallic contaminants from a residual asphaltic petroleum fraction the major portion of which boils above about 900° F. containing metallic contaminants which comprises contacting said petroleum fraction at a temperature gradient in the range between 750° and 825° F. with a sulfur-insensitive cobalt molybdate hydrogenation catalyst in the presence of hydrogen at a pressure in the range from 400 to 3000 pounds per square inch gauge and at a space velocity in the range between 0.25 and 5.0 v./v./hr. to form microcoke particles separable from the contacted fraction and containing said contaminants, removing said contacted fraction from contact with said catalyst, separating said microcoke particles from said contacted fraction, and recovering said contacted fraction containing a substantially reduced amount of metallic contaminants.

2. A method in accordance with claim 1 in which the microcoke particles are separated by centrifuging.

3. A method in accordance with claim 1 in which the microcoke particles are separated by filtering.

4. A method for removing organic metallic contaminants from a residual asphaltic petroleum fraction boiling above about 900° F. containing organic contaminants which comprises contacting said petroleum fraction at a temperature in the range between 750° and 825° F. with a sulfur-insensitive cobalt molybdate hydrogenation catalyst in the presence of hydrogen at a pressure in the range from 400 to 3000 pounds per square inch gauge and at a space velocity in the range between 0.25 and 5.0 v./v./hr. to form microcoke particles separable from the contacted fraction and containing said organic contaminants, removing said contacted fraction from contact with said catalyst, separating said microcoke particles from said contacted fraction, and recovering said contacted fraction containing a substantially reduced amount of organic metallic contaminants.

5. A method in accordance with claim 4 in which the microcoke particles are separated by centrifuging.

6. A method in accordance with claim 4 in which the microcoke particles are separated by filtering.

7. A method for removing organic metal contaminants from a residual asphaltic Venezuelan petroleum fraction boiling above about 900° F. containing metal contaminants which comprises contacting said petroleum fraction at a temperature gradient in the range between 775° and 825° F. with a sulfur-insensitive cobalt molybdate hydrogenation catalyst in the presence of hydrogen at a sufficient pressure in the range from 400 to 3000 pounds per square inch gauge and at a space velocity in the range between 0.25 and 5.0 v./v./hr. to form microcoke particles separable from the contacted fraction and containing said organic metal contaminants, removing said contacted fraction from contact with said catalyst, separating said microcoke particles from said contacted fraction, and recovering said contacted fraction contain-

ing a substantially reduced amount of organic metal contaminants.

8. A method for removing organic metallic contaminants from a residual asphaltic petroleum fraction boiling above about 900° F. containing metal contaminants which comprises contacting said petroleum fraction at a temperature gradient in the range between 775° and 825° F. with a sulfur-insensitive cobalt molybdate hydrogenation catalyst in the presence of hydrogen at a sufficient pressure in the range from 400 to 3000 pounds per square inch gauge and at a space velocity in the range between 0.25 and 5.0 v./v./hr. to form microcoke particles separable from the contacted fraction and containing said organic metal contaminants, removing said contacted fraction from contact with said catalyst, separating said microcoke particles from said contacted fraction, and recovering said contacted fraction substantially free of organic metallic contaminants. 10

9. A method for removing metal contaminants from a residual asphaltic Venezuelan petroleum fraction boiling above about 900° F. containing metal contaminants which comprises contacting said petroleum fraction at a temperature in the range between 775° and 825° F. with a sulfur-insensitive cobalt molybdate hydrogenation catalyst in the presence of hydrogen at a sufficient pressure 20

15

25

in the range from 400 to 3000 pounds per square inch gauge and at a space velocity in the range between 0.25 and 5.0 v./v./hr. to form microcoke particles separable from the contacted fraction and containing said metal contaminants, removing said contacted fraction from contact with said catalyst, separating said microcoke particles from said contacted fraction, and recovering said contacted fraction substantially free of metal contaminants.

10. A method in accordance with claim 1 in which the microcoke particles are separated by gravity settling.

11. A method in accordance with claim 4 in which the microcoke particles are separated by gravity settling.
